UNITED STATES PATENT OFFICE.

BERNARD A. STERLING, OF CHICAGO, ILLINOIS.

HAIR-WAVER.

1,384,166.

Specification of Letters Patent. Patented July 12, 1921.

Application filed October 20, 1919. Serial No. 331,944.

To all whom it may concern:

Be it known that I, BERNARD A. STERLING, a citizen of the United States, residing at Chicago, in the county of Cook and State of Illinois, have invented a certain new and useful Improvement in Hair-Wavers, of which the following is a full, clear, concise, and exact description, reference being had to the accompanying drawings, forming a part of this specification.

My invention relates to improvements in hair waving devices and has special reference to an improved device for placement upon the head for waving and crimping the hair of the user.

A particular object of my invention is to produce upon the head of the user what are known as Marcel waves which are peculiar in their character in that the hair has a combined vertical and transverse waving combined with more or less sharply defined crimps and depressions. Heretofore such effects have required the expert manipulation of a trained hair dresser, but by means of my invention the user is enabled to produce the most artistic Marcel waves, substantially automatically, and without any extended previous training.

This present invention is a further development and improvement upon my invention of hair waver as disclosed in my co-pending application filed September 15, 1919, Serial Number 323,762.

The device of my invention comprises an elongated rigid member around which the strand of hair is adapted to be wound, and for the purpose of assisting the user in holding the member rigidly while winding the strand of hair, I hingedly connect a second member to the first member, providing a limiting hinging movement so that the second member stands at an angle to the first member during the operation of winding on the strand of hair and assists in the holding of the member against the strain of winding the strand of hair upon it.

The first member has a central longitudinal rib on its upper face and the second member has a longitudinal slot; the second member is adapted to be pressed down upon the hair after the hair is wound around the first member to force the hair down into the re-entrant corners at the sides of the rib, thus clamping the hair tightly over the edge of the rib, which is V-shaped and producing several sharply defined creases or crimps in

the hair being waved. I make these two members each out of a single piece of material such as sheet celluloid and I hinge them together in a peculiar manner which is very simple and cheap and yet prevents the complete separation of the two members and provides the limited hinging function mentioned.

In this form of my invention I also provide a sleeve-like inclosing or clamping member adapted to be pushed endwise over the two members, when in clamping position, and over the hair wound thereon and clamp the slotted member tightly down upon the hair and toward the main member to increase the crimping and waving effect of the device and retain the hair and the members in compact relation during the time that the device is on the head and effecting the crimping or waving of the hair.

My invention will be more readily understood by reference to said drawings, in which:

Figure 1 is a side elevation of the device, the several parts being arranged in hair crimping relation and the strand of hair indicated in dotted lines, and the open position of the slotted member being shown in dotted lines;

Fig. 2 is a plan view of the device without the clamping sleeve;

Fig. 3 is a vertical sectional view on the line 3—3 of Fig. 1;

Fig. 4 is a perspective view of the sleeve clamp; and

Fig. 5 is a fragmentary bottom elevation of the hinged ends of the two members.

In said drawings 1 is the base or main member which is elongated and narrow and is provided with a central longitudinal vertical rib 2 which extends substantially from end to end thereof and is provided with a relatively sharp V upper edge 3. The strand of hair 4 is adapted to be wound around this member from end to end in spiral form as indicated in dotted lines in Fig. 1.

The lateral edges of the member 1 are provided with deep V-shaped notches 5 to receive the strand of hair and assist in effecting the crimping effect thereof. Preferably the V-shaped notches on the two sides of the member 1 are offset as indicated in Fig. 2.

The longitudinal rib 2 provides reentrant corners 6 between its lower portion and the upper face of the base member 1. To produce the artistic Marcel wave effect which is

desired, I press the upper part of the wound strand of hair down upon the V-shaped edge 3 of the member 2 and down into said reentrant corners, tightly drawing the 5 strands of hair into the notches 5 and around the lateral edges of the base member 1 by means of a holding or clamping member 7, which, like the member 1, is elongated, but instead of being provided with a rib is 10 provided with a longitudinal slot 8 for straddling the rib 2 and pressing the turns of hair tightly down at each side of the rib 2.

I loosely hinge one end 9 of the member 15 7 to one end 10 of the member 1 by a peculiar hinge construction which can be produced at a minimum of cost. I make each 20 of these members out of a single piece of material such as sheet celluloid and for hinging them together I provide the end 10 of the member 1 with a transverse slot 11 and I provide the member 7 with a T-head 12 upon the outer or free end of the neck portion 13. The T-head is rounded on its outer edge 14 25 and is square on its inner edge 15. As best illustrated in Fig. 5, the relative dimensions of the slot 11 and the neck 13 are such that when the T-head is pushed to one side of the slot as far as it can go the opposite prong 30 of the head cannot pass through the slot after it has once been entered. However, this overlap of the prong on the T-head is relatively so slight that in forcing the T-head through the slot the material of which 35 the members are made yields or gives sufficiently so that the prong passes through the slot and thereafter the T-head cannot be removed from the slot on account of the square inner edge, the rounded edge 14 acting 40 as a wedge to spread the two members and elongate the slot as the T-head is forced through the slot.

For holding the opposite ends of the two members in interlocked relation during the 45 use of the device, I provide a transverse slot 16 in the free end of the member 1 and I provide a narrow tongue 17 on the free end of the member 7 adapted to slide freely through the slot 16, and for facilitating the 50 entrance of the tongue 17 through the slot 16 I curve the free end 18 containing the slot 16 upwardly and I offset the end 17 of the member 7 downwardly as best shown in Fig. 1. In entering the tongue into the slot 55 16 the member 7 is curved upwardly between its ends sufficiently to draw the extreme end of the tongue 17 back far enough to freely enter into the slot 16.

As the slot 8 is relatively wide so as to 60 span the upper part of the coiled body of hair on the member 1, each side of the rib 2, as best shown in Fig. 3, the side bars 19 of the member 7 are relatively weak, and not strong enough to compress the hair properly 65 down into the reentrant corners 6 and draw

the strand tightly around the edge 3. I provide a holding or clamping member, which is in the form of a split sleeve 20, the longitudinal edges 21 thereof being separated to span the longitudinal rib 2 and the strand of hair which is wound around the member 1 as best shown in Fig. 3. This sleeve is a member separate from the other parts of the device and adapted to be placed lengthwise over the members 1 and 7 when in clamping 75 position, the under surfaces of the side edges of the sleeve being adapted to bear down upon the side bars 19 of the member 7 and press the same toward the base 1 and compress the strand of hair between said side 80 bars and the base 1, forcing it into the angles 6 and also squeezing the strand of hair up against the lower side of the base 1 and into the V-shaped notches 5, at the edges of the base. In order that the sleeve 20 may be 85 readily placed in position upon the device and removed therefrom the ends 22 thereof are slightly flared outwardly, so that the device will readily pass over the hair without catching on same, the inner corners being removed as best shown in Fig. 4.

In using my device, the two members 1 and 7 are first placed in the position shown in Fig. 1, the member 7 being in its dotted position, affording a good hand grip, and the strand of hair 4 is then wound spirally thereon, beginning at the hinged end of the device and ending at the opposite end, after which the member 7 is depressed upon the strand of hair straddling the rib 2 and its free end is inserted through the slot 16 to hold it in position. Then the strand of hair, as shown at 23, is drawn back along the lower side of the device and afterward the clamping sleeve 10 is entered upon the device from the free ends thereof in the direction of the arrow on Fig. 1, thereby pressing the bars 19 tightly down upon the interposed strand of hair and holding the free end of the strand tightly up against the 110 lower part of the wound strand. The device is left upon the hair a suitable length of time, usually over night, and when removed and the strand of hair loosened up, it is found to be crimped or waved in the form 115 of a Marcel wave with characteristic undulations and definite crests and depressions which distinguish the most artistic Marcel waves.

As many modifications of my invention 120 will readily suggest themselves to one skilled in the art, I do not limit or confine my invention to the specific structures herein shown and described, except within the scope of the appended claims.

I claim:

1. In a hair waver adapted for waving hair on the head of the user, comprising a flat base bar, a longitudinally extending thin central rib on its upper face, a longi- 130

tudinally slotted member hinged at one end to the base member and adapted to straddle the rib, means for securing the free end of the slotted member to the free end of the base member, and a split clamping member adapted to surround the base and the side bars of the slotted member and hold the two members tightly clamped upon the strand of hair to be waved.

10 2. In a hair waver, a member, around which the strand of hair is adapted to be wound in a spiral, and a longitudinally extending central rib on its upper face, a slotted member for straddling said rib and holding the hair down on each side thereof, and a split ring clamping member for surrounding the other two members and the hair wound thereon, and holding the two members clamped together on the hair, the opposed edges of the split being separated to span said rib.

25 3. In a hair waver, a substantially rigid base member having a longitudinal central rib on its upper face, a yielding clamping member loosely hinged at one end to one end of the base member by a hinge connection limiting the outward swinging motion of the clamping member, and a split sleeve for placement endwise upon the two members when in clamping position for holding the members tightly clamped upon each other and upon the hair being waved.

30 4. In a hair waver, an elongated relatively rigid member around which a strand of hair is adapted to be wound for crimping or waving same, and having a central longitudinal rib on one face, a slotted member for pressing the hair onto the rigid member at each side of the rib, and a clamping sleeve for surrounding said members and holding the slotted member pressed tightly into position, said sleeve having flared ends for facilitating its placement and removal.

45 5. In a hair waver, a flat elongated member, a rib disposed on one side of the elongated member, said elongated member and rib adapted to have the strand of hair wound in a series of curls thereon, a compression member carried by said elongated member for compressing the hair while in a series of curls, and means for varying the tension of said compression member.

55 6. In a hair waver, a flat elongated member, a projection disposed on one side of the elongated member to form a ridge thereon, said elongated member and projection adapted to have a strand of hair wound in a series of curls thereon, a compression member having a slot formed therein carried by said elongated member, said projection lying in said slot when the compression member is in operative position, and means

binding said compression member against the elongated member to impart a series of waves to said hair.

65 7. In a hair waver, a retaining member having a plurality of cuts along the longitudinal sides, a ridge formed thereon over which strands of hair are wound in a series of curls, a pivotal member adapted to have a clamping position on the retaining member, said pivotal member having a slot cut therein to clear said ridge when in clamping position, means for locking said pivotal member in clamping position whereby the hair will be compressed to bind against the ridge and retaining member, said cuts in said retaining member causing the hair to wave in a series of curls transverse to the strands of hair.

70 8. In a hair waver, a hair retaining member, a rib formed thereon over which a strand of hair is wound in a series of curls, a compression member adapted to lie upon said retaining member and having a slot formed therein to clear said rib, and a clip adapted to be mounted on said retaining member and compression member to increase the tension of said compression member so as to compress the hair about the rib.

85 9. In a hair waver, a hair retaining member of an irregular cross section to form a plurality of indents in the periphery, a compression member carried by and adapted to lie upon said retaining member when in closed position so as to compress and bind the hair in said indents, an enlarged head formed at one end of the compression member, said hair retaining member having a slot cut therein of a smaller dimension than said head, said head adapted to be forcibly inserted in said slot to permanently lock said two members together in a hinge joint, and means for retaining the opposite ends of the members in closed position.

95 10. In a hair waver, a hair retaining member having an irregular cross section so as to form a plurality of indents in the periphery, a compression member carried by and adapted to lie upon said retaining member when in closed position so as to compress and bind the hair into said indents, and a clip member slidably carried for engaging the compression member to increase the tension thereof.

100 11. In a hair waver, a member upon which hair is adapted to be wound, a compression member lying face to face upon the hair retaining member, and means independent of either for retaining said compression member against the hair retaining member so as to compress the hair about the same.

115 In witness whereof, I hereunto subscribe my name this 18th day of October, 1919.

BERNARD A. STERLING.
